DESIGN FOR A NAVIGATIONAL INSTRUMENT

Thomas C. Green, United States Marine Corps

Application December 23, 1942, Serial No. 109,116

Term of patent 3½ years

To all whom it may concern:

Be it known that I, Thomas C. Green, a citizen of the United States and an officer in the United States Marine Corps, have invented a new, original, and ornamental Design for a Navigational Instrument, of which the following is a specification, reference being made to the accompanying drawing, forming part thereof.

Fig. 1 is a plan view of a navigational instrument showing my new design; and

Fig. 2 is a sectional view on line 2—2 of Fig. 1.

I claim:

The ornamental design for a navigational instrument, as shown.

THOMAS C. GREEN.
